Patented Aug. 31, 1965

202,135

TOP FOR A CARTON OR THE LIKE

Richard Sisco, 470 Knollwood Road, Ridgewood, N.J.

Filed Sept. 4, 1964, Ser. No. 81,601

Term of patent 14 years

(Cl. D58—26)

Fig. 1

Fig. 2

Fig. 3

Fig.4

Fig.5

I claim:

The ornamental design for a top for a carton or the like, as shown and described.
